(57) CLAIM

The ornamental design for a toothbrush, as shown and described.

DESCRIPTION

FIG. 1 is a top, front, and left side perspective of a toothbrush embodying my new design.

FIG. 2 is a front elevation view thereof.

FIG. 3 is a rear elevation view thereof.

FIG. 4 is a left side view thereof, the right side being a mirror image.

FIG. 5 is a top plan view thereof; and,

FIG. 6 is a bottom plan view thereof.

Shown in phantom lines are bristle features, button features and grip features of the toothbrush which form no part of the claimed design.
